UNITED STATES PATENT OFFICE.

ANNA E. NEITZ, OF NEW YORK, N. Y.

IMPROVEMENT IN COOKING APPARATUS.

Specification forming part of Letters Patent No. 146,142, dated January 6, 1874; application filed April 11, 1873.

To all whom it may concern:

Be it known that I, A. E. NEITZ, of New York city, have invented certain new and useful Improvements relating to Cooking Apparatus, of which the following is a specification:

The apparatus is intended for use in families, large or small, for cooking in warm weather. It is adapted for the burning of charcoal. A fire may be made rapidly, and maintained in a vigorous condition for a brief period, sufficient for the cooking, and then allowed to expire.

The following is a description of what I consider the best means of carrying out the invention.

The accompanying drawings form a part of this specification.

Figure 1 is a vertical longitudinal section, showing a simple form of the apparatus arranged for cooking not only soup or the like in the main vessel, but also something in a frying-pan mounted above. Fig. 2 is a plan view of the same, a portion being represented as broken away. Fig. 3 is a vertical section, showing a more complex apparatus so far as relates to the main vessel. The soup or the like is in a supplementary vessel, and the main vessel may, at pleasure, contain only water, or may contain other food. In this figure, the central flue is prolonged upward by the use of an additional piece.

Similar letters of reference indicate corresponding parts in all the figures.

A is a vessel, of sheet-tin or other suitable material, supported upon legs a, and having a large open tube, A¹, extending up through its bottom to a little above the top. The fire is made in this tube, and is thus completely inclosed by the water, soup, or other material which it is intended to cook. The fuel rests upon a grate, B, which is adapted to slide in grooves a'. On withdrawing the grate at the close of a cooking operation, the relics of the fire may be dropped. I propose to employ a pan, M, to receive the fire in such case, and to receive any dropping ashes or sparks which may be emitted during the progress of the fire; but the pan may be in some cases omitted by resting the legs upon the hearth or any incombustible support. A² is a stop-cock, by which the water may be drawn from the ves-

sel A. When the contents of the vessel A are too thick to be thus removed, the vessel may be lifted and turned over after the fire has been dropped by the removal of the grate. C is a cover adapted to keep in the heat. It fits upon the vessel A, with a suitable hole to receive the upper end of the tube A¹. On the top of the cover are fixed arms c, adapted to support a frying-pan, E, and thus hold it exposed to the active current of hot gas rising from the tube A¹. The capacity of the internal chamber A¹, which I have designated as a tube, may be made greater at the bottom than at the top. It is preferable that it shall be without seam, and it is important that it shall be adapted to withstand a higher temperature, particularly at its upper portion. The upper end may be advantageously formed of a size to exactly match some of the standard sizes of stove-pipe, pieces of which may be attached, with elbows, or otherwise led into a chimney, so that the fumes of the charcoal may escape. G is a piece especially adapted to so apply, and H is a close-fitting cover, on applying which the draft of the fire will be stopped. D is a supplementary vessel, of a form corresponding to the vessel A, and having a corresponding internal tube, D'.

In cooking certain kinds of food the vessel A contains simply water, and the cooking is effected in the vessel D, with the effect of modifying the heat to which the contents of the vessel D is exposed, on the principle employed in the common farina-kettle.

The apparatus in other respects may be the same as before described. The apparatus may be modified in form without sacrificing all the advantages of the invention.

Handles may be attached to any convenient point to aid in the manipulation. A spout may be formed at a desired point at the end or side. I can employ two or more of the internal tubes A¹ D', in order to inclose the heating-surface. I can employ one set considerably out of the center, to allow more room for the introduction of an ordinary pail or other vessel to be surrounded by the hot water. I can provide a partition across the vessel to allow the separate cooking of two kinds of food without mixing, if desired.

Instead of removing the grate B by drawing

it out, it may form a part of a platform, to which the legs are attached, and on which the vessel A rests. The platform and grate may, in such case, be made of cast-iron, and, furthermore, may be formed with an open-work frame, extending up a little way within the tube A¹, so as to retain the relics of the fire and prevent their scattering about when the vessel A is lifted off. In such case the grate may, if preferred, be sunk a little below the platform, so as to bring the fire a little lower.

I claim as my invention—

1. The open-topped vessel A A¹, supports a, and pan M, in combination with supplementary

vessel D D' and removable grate B, for joint operation, as herein specified.

2. The supporting-arms c, adapted to support frying-pan E, in combination with vessel A A¹, supports a, and removable grate B, as herein specified.

In testimony whereof I have hereunto set my hand this 10th day of April, 1873, in the presence of two subscribing witnesses.

ANNA E. NEITZ.
